[57] ABSTRACT

A strong acid catalyzed alkylation process wherein an isoparaffin is alkylated with an alkylating agent such as olefin hydrocarbon, alkyl sulfates, in the liquid phase, at a superatmospheric pressure and a temperature in the range of from below zero to about 100°F., and wherein gaseous carbon dioxide is dissolved in the strong acid catalyst.

5 Claims, No Drawings

ISOPARAFFIN ALKYLATION

BACKGROUND OF THE INVENTION

The present invention relates to alkylation of isoparaffin hydrocarbons with olefins in the presence of a strong acid catalyst. Particularly, the invention relates to production of C₇-C₈ hydrocarbon suitable for use as motor fuel by alkylation of isoparaffin hydrocarbon with olefins. More particularly, this invention relates to an isobutane-butylene alkylation process catalyzed by sulfuric acid and/or fluorsulfonic acid, having high selectivity for production of trimethyl pentanes.

Acid catalyzed alkylation wherein an alkane is added to an alkene is well known. The alkylation reaction is generally carried out in the liquid phase at a temperature usually below about 100°F. and at a pressure sufficient to maintain reactants in the liquid phase. Of particular importance is alkylation of isobutane with butylene to form octane hydrocarbons, especially trimethyl pentanes, which are useful as components of motor fuel. The butylenes which may be a mixture of normal and isobutylenes are reacted with a molar excess of isobutane in the liquid phase in the presence of a strong acid such as sulfuric acid, fluorsulfonic acid, and mixtures thereof, at a temperature of 0°F. to 100°F. and a pressure of 10 to 150 psig, or higher.

The discussion herein is presented with respect to formation of octane hydrocarbons, however, it is to be understood that the discussion is equally applicable to alkylation reactions generally, and particularly to alkylation of isobutane and isopentane with lower molecular weight olefins such as propylene, butylenes, and pentalenes. Basically, it is desirable in an alkylation reaction to promote formation of the 1:1 olefin-paraffin adduct. That is, formation of octane from butylenes and paraffins. In strong acid catalyzed alkylation reactions, side reactions occur in which C₁₂⁺ products are formed as well as the desirable 1:1 olefin-paraffin adduct. A portion of C₁₂⁺ products then undergo cracking to form undesirable lighter hydrocarbons, such as for example, C₅, C₆, and C₇ light alkylate hydrocarbons. The result of such side reactions, then, is to reduce production of the desired C₈ products and to lower the octane number of the alkylate product obtained.

SUMMARY OF THE INVENTION

Now, according to the method of the present invention, an improved strong acid catalyzed alkylation process is disclosed wherein production of desirable 1:1 olefin-isoparaffin adduct is increased. In the method of the present invention, olefin hydrocarbon is reacted with a molar excess of isoparaffin hydrocarbon at a temperature of from about 0°F. to about 100°F., a pressure of about 10 psig to about 150 psig and higher, in the presence of a carbon dioxide treated strong acid catalyst such as sulfuric acid, fluorsulfonic acid and mixtures thereof. In a preferred embodiment, the carbon dioxide treated strong acid catalyst is prepared by contacting liquid strong acid with carbon dioxide gas at a temperature in the range of 0°F. to 75°F., a pressure in the range of 50 psig to 1000 psig and under conditions of good mixing to dissolve carbon dioxide into the strong acid.

By employing the improved carbon dioxide treated strong acid catalyst of the present invention in an alkylation process, formation of desirable 1:1 olefin-isoparaffin adduct is increased over that obtained from an

alkylation process wherein untreated strong acid catalyst of the prior art is employed. Additionally, formation of undesirable, low octane number light alkylate and heavy alkylate hydrocarbons is decreased. In an alkylation process of the present invention, employing a carbon dioxide treated strong acid catalyst, wherein isobutane is alkylated with butylenes, octane hydrocarbons are the major product of the process. Also, the major portion of the octane hydrocarbon alkylate is comprised of trimethyl pentanes which have high octane numbers and are particularly desirable as components for gasoline blending. Reduction of light alkylate components and C₈⁺ heavy alkylate components, by following the method of the present invention, improves volatility characteristics of the alkylate product. These, and other advantages will be more fully set out in the detailed description of the invention which follows.

DETAILED DESCRIPTION OF THE INVENTION

Unexpectedly, according to the present invention, we have discovered that incorporation of carbon dioxide gas into liquid alkylation acid catalysts improves subsequent alkylation reactions by increasing the yield of desirable 1:1 isoparaffin-olefin adducts, particularly the desirable highly branched isomers. The reasons for such improvement are not presently known. It may be speculated that solution of carbon dioxide into the acid catalyst reduces the acid viscosity such that better mixing of hydrocarbon reactant and catalyst is obtained, or that hydrocarbon solubility in the acid catalyst is increased. However, such speculations are unsupported and are not to be taken as limitations upon the present invention.

Carbon dioxide treatment according to the method of the present invention is applicable to strong Brönsted acid alkylation catalysts. The strong Brönsted acids are those which readily give up a proton, and include HF as well as H₂SO₄, H₂SO₄-SO₃, H₂SO₄-H-SO₃F, H₂SO₄-HSO₃Cl, and H₂SO₄-HB(HSO₄)₄. Such acids are the catalysts used in the (C₄ to C₁₀) isoparaffin - (C₃ to C₁₀) olefin alkylation reactions. Particularly, carbon dioxide treatment improves selectivity of sulfuric acid, fluorsulfonic acid, and mixtures thereof for formation of desirable 1:1 isoparaffin-olefin adducts in an alkylation reaction. Especially, carbon dioxide treated sulfuric acid has improved selectivity for production of trimethyl pentanes in an alkylation reaction employing isobutane and butylene reactants.

Strong acid alkylation catalyst is treated with carbon dioxide gas under conditions to dissolve carbon dioxide into the liquid catalyst. Preferably, liquid acid and gaseous carbon dioxide are contacted under conditions of intimate mixing at superatmospheric pressures and temperatures in the range of below zero to 100°F. More preferably, pressures in the range of about 50-1000 psig and temperatures in the range of 20°-75°F. are employed. Higher pressures and lower temperatures favor solution of carbon dioxide in the liquid strong acid. Pressures of atmospheric and higher are effective, and pressures of at least 50 psig are preferred. Pressures greater than about 1000 psig do not offer any substantial economic advantage. Lower temperatures favor solution of carbon dioxide in liquid strong acid. At temperatures below about 20°F., liquid viscosity increases substantially and extra refrigeration must be provided. Temperatures in the range of about 20°-60°F. are

within the usual temperature range of the alkylation reactions contemplated herein, thus extra refrigeration to cool the liquid strong acid is not required. Benefits of the present invention are obtained by dissolving carbon dioxide into the liquid strong acid catalyst. Maximum benefits are obtained when the strong acid is saturated with carbon dioxide at the alkylation reaction conditions employed. In order to encourage solution of carbon dioxide in strong acid, it is usually desirable to employ an excess of carbon dioxide. In treating the strong acid, weight ratios of carbon dioxide to strong acid of about 0.1/100 and higher may be employed. Preferably weight ratios of carbon dioxide to strong acid of at least 5/100 are employed. Great excesses of carbon dioxide to strong acid in the acid treatment are not necessary, and excess carbon dioxide which does not dissolve in treated strong acid may be recovered for treatment of additional acid.

Intimate mixing of carbon dioxide gas with liquid strong acid may be accomplished by any effective gas-liquid contact means such as aspiration, sparging, agitation, etc. In a preferred mode of operation, carbon dioxide and strong acid are contacted before employing the treated strong acid as catalyst in an alkylation reaction. In processes wherein alkylation acid is recycled from an acid settler to an alkylation reaction zone, the recycle acid may be conveniently treated with carbon dioxide in a separate treating zone prior to introduction into the alkylation reaction zone. However, if desired, the carbon dioxide may be introduced directly into the alkylation reaction zone with mixing means provided to ensure contact of acid catalyst with hydrocarbon reactants also being used to contact the acid catalyst with the carbon dioxide.

Contact time of carbon dioxide with strong acid being treated need only be sufficient for solution of the desired amount of carbon dioxide into the strong acid. Contact times of from a few seconds to 24 hours and longer may be employed. Necessary contact time will be shorter with better mixing and more intimate contact of carbon dioxide with the strong acid. Preferred contact times for any particular acid treating system may be easily established by observing the rate of solution of carbon dioxide into the strong acid under the conditions of pressure, temperature and degree of mixing present in the particular system under consideration.

Conventional strong acid catalyzed alkylation reactions may be carried out employing the improved process of the present invention. Thus, the alkylation can comprise reaction of an isoparaffin with an olefin or other alkylating agent. In sulfuric acid and flurosulfonic acid catalyzed alkylation reactions, alkyl sulfates, such as diisopropylsulfate, diisobutylsulfate, dibutylsulfate, etc., may replace the corresponding olefin in whole or in part as alkylating agent.

The alkylation reactions contemplated in the present invention are carried out in the liquid phase. However, the reactants need not be normally liquid hydrocarbons. Alkylation reaction conditions can vary in temperature from below zero to about 100°F., and can be carried out at pressures of from atmospheric to 1000 psig and higher. For continuous processes, olefin space velocities of from about 0.01 to about 20 volumes olefin/hour/volume of catalyst may be employed. Molar ratios of isoparaffin hydrocarbon to alkylating agent of from about 1:1 to about 50:1 and higher may be em-

ployed. Preferably, substantial molar excess of isoparaffin to olefin is maintained in an alkylation reaction, with molar ratios of isoparaffin to olefin of from about 5:1 to about 20:1 being particularly preferred.

Strong acid alkylation catalysts can be employed in the alkylation reactions. However, sulfuric acid and mixtures of sulfuric acid and flurosulfonic acid are preferred. In the process of the present invention, where a carbon dioxide treated strong acid catalyst is employed, the preferred temperatures for use of sulfuric acid are between 30° and 75°F. and preferred pressures are 50 psig to 150 psig and higher. When using flurosulfonic acid as catalyst, preferred temperatures are between 0° and 75°F. and preferred pressures are 50 psig to 150 psig and higher.

The following examples are offered to illustrate the improvement of the present invention.

EXAMPLE I

To demonstrate the present invention, 300 ml. of 94.43 weight percent sulfuric acid, containing 30 ml. of acid from a previous alkylation run, was charged to a reactor equipped with cooling coils and a stirrer. The autoclave was pressured to 100 psig with CO₂ and the acid was stirred at about 50°F. for 15 minutes. Upon completion of the stirring, the autoclave was depressured to 50 psig and 77 grams of hydrocarbon comprising isobutane and butene-2 in a volume ratio of 6.25/1 was charged to the reactor. Under alkylation conditions including a temperature of 50°F., a pressure of about 105 psig and constant stirring, the acid-hydrocarbon mixture was allowed to react for 15 minutes. At the end of the reaction time the stirring was stopped and the reaction mixture was separated into an acid phase and a hydrocarbon phase.

In a second run, for comparative results, the experiment above was repeated, except nitrogen was substituted for carbon dioxide in the acid treating step prior to the alkylation reaction.

The hydrocarbon phase from each run above was separately fractionated to recover pentane and heavier alkylate therefrom, and the recovered alkylate fractions were subjected to analysis. Results of such analysis are reported in Table I below.

TABLE I

	CO ₂	N ₂
Alkylate yield, basis olefin consumed (wt.%)	158	185
Alkylate Composition (Vol.%)		
C ₅	2.3	3.6
C ₆	4.8	5.6
C ₇	4.7	5.7
C ₈	56.4	53.6
C ₉ +	31.9	31.4
Alkylate Bromine No.	2.6	3.8
C ₈ Distribution (Vol. % of Alkylate)		
Trimethyl pentane	43.1	36.9
Dimethyl hexane	3.0	3.6
Unidentified C ₈	10.3	13.1

From the Table I it can readily be seen that the alkylation reaction employing carbon dioxide treated sulfuric acid catalyst was more selective for production of desirable C₈ range alkylate, and particularly for production of desirable trimethyl pentanes than was the alkylation reaction employing nitrogen treated sulfuric acid catalyst. Additionally, the bromine number, indicating degree of unsaturation, was lower for alkylate

produced in the reaction using the carbon dioxide treated sulfuric acid catalyst.

EXAMPLE II

In the same reactor system employed in Example I, additional alkylation reactions were performed to show the advantage of using the carbon dioxide treated sulfuric acid of the present invention, as compared to alkylation reactions using untreated sulfuric acid. Summaries of operating conditions and analytical results for these alkylation runs are shown in Table II below.

TABLE II

Run Number	1	2	3	4	5	6	7
Acid (M)	100	100	100	100	100	100	100
H ₂ SO ₄ (wt. % in acid)	94.6	96.13	96.13	96.1	94.6	96.13	94.6

C ₉ +	17.0	25.6	25.1	27.9	30.7	22.6	26.7
Alkylate Bromine Number	1.7	3.0	3.4	4.2	5.4	3.0	4.6
C ₈ fraction composition (Vol. % of Alkylate)							
Trimethyl pentane	58.0	49.2	50.9	47.0	42.8	46.2	43.3
Dimethyl hexane	4.7	3.2	—	3.8	4.4	4.9	4.6
Unidentified C ₈	9.6	10.5	11.7	9.8	13.3	12.0	11.1

Runs 1 through 4 were made employing carbon dioxide treated sulfuric acid alkylation catalyst. In run 1, sulfuric acid was mixed with carbon dioxide at 600 psig and 50°F. for 48 hours. At the end of this time, pressure was reduced and the alkylation reaction was performed at 95 psig. In Runs 2-4, carbon dioxide was added to the sulfuric acid in the reaction vessel, in the weight fractions shown and the alkylation reactions were performed at the resulting pressures. For runs 5-7, no additive was employed with the sulfuric acid catalyst.

From an examination of the results obtained in this example, alkylation runs employing carbon dioxide treated sulfuric acid catalyst produce greater yields of alkylate, as a weight percent of olefin consumed in the reaction, than alkylation runs employing untreated acid catalyst. Also, the alkylate from the treated catalyst runs contains greater amounts of C₈ hydrocarbons, particularly the desirable trimethyl pentane isomers. As indicated by the Bromine number, olefin content of alkylate produced with treated catalyst is lower than for alkylate produced with untreated catalyst.

From the foregoing discussion and examples, the advantages of the improvement of the present invention can readily be seen. By employing a carbon dioxide treated sulfuric acid alkylation catalyst in the alkylation of lower molecular weight isoparaffin hydrocarbons with olefins having three to five carbon atoms, alkylate of improved quality can readily be obtained.

Obviously, many modifications and variations of the

invention, as hereinabove set forth, may be made without departing from the spirit and scope thereof. Therefore, only such limitations should be imposed as are indicated in the appended claims.

We claim:

1. In an alkylation process wherein isoparaffin hydrocarbon selected from the group consisting of isobutane, isopentane and mixtures thereof is alkylated with an alkylating agent selected from the group consisting of propylene, butylenes, pentylenes, their sulfates, and mixtures thereof in the liquid phase, in the presence of

- 35 an acid catalyst selected from the group consisting of sulfuric acid, fluorosulfonic acid, and mixtures thereof at a temperature in the range of about zero to about 100°F and a superatmospheric pressure; the improvement which comprises:
- 40 a. treating said acid catalyst with carbon dioxide to form an acid catalyst having a weight ratio of carbon dioxide to acid of at least 0.1/100 at a temperature in the range of about zero to about 100°F and a superatmospheric pressure in the range of from about 50 psig to about 1000 psig; and
- 45 b. alkylating said isoparaffin hydrocarbon with said alkylating agent in the presence the carbon dioxide treated acid catalyst of step (a).
- 50 2. The process of claim 1 wherein the treating step (a) temperature is in the range of about 20°F to about 75°F, the pressure is in the range of about 50 psig to about 1000 psig, and the acid catalyst is contacted with carbon dioxide in a weight ratio of carbon dioxide to acid in the range of about 0.3/100 to about 5/100.
- 55 3. The process of claim 2 wherein treated acid catalyst from step (a) contains from about 0.3 to about 0.8 weight percent carbon dioxide.
4. The process of claim 3 wherein isoparaffin reactant is isobutane and the alkylating agent is selected from the group consisting of propylene, butylenes, pentylenes and mixtures thereof.
5. The process of claim 4 wherein the acid catalyst is sulfuric acid.
